MASTER AND BLOCK-OUT SHEET GRIPPER
MEANS FOR ROTARY DUPLICATING MA-
CHINESWilhelm Ritzerfeld, Berlin-Dahlem, and Gerhard
Ritzerfeld, Berlin-Grunewald, Germany

Application January 21, 1953, Serial No. 332,432

Claims priority, application Germany
April 24, 1952

7 Claims. (Cl. 101—132)

1

The present invention relates to duplicating machines for printing texts from printing masters, for example mirror-script originals, on copy sheets. In such a rotary duplicating machine, the printing master is attached to a rotary printing drum by means of a clamping device comprising a movable clamping jaw for closing and opening the clamping device. The closing and opening of the clamping device for attaching a printing master and for releasing the same after the printing has been completed is effected in known manner by a manually operable actuating lever. For certain duplicating purposes it is necessary to attach more than one printing master or a printing master and a sheet covering the same in part to the printing drum.

It is an object of the invention to provide means for facilitating attaching more than one printing master, or a printing master and a covering sheet, to a rotatable printing drum of a rotary duplicating machine.

Other objects and advantages will become apparent from the following detailed description of an embodiment of the invention, when read in conjunction with the appended drawings in which:

Fig. 1 is a side view, partly in section along the line C—D of Fig. 2, of an embodiment of the invention;

Fig. 2 is a section along the line A—B of Fig. 1; and

Fig. 3 illustrates a portion of Fig. 1 in a different position.

The present invention consists in a rotary duplicating machine comprising at least two clamping devices arranged immediately one behind the other when viewed in the direction of rotation of a rotatable printing drum of the machine, the two clamping devices being immovable relatively to the printing drum in the axial direction thereof, a clamping jaw of each clamping device being movable in the direction substantially perpendicular to the axis of the printing drum for opening and closing the respective clamping device whereby one of the clamping devices may receive an edge of a printing master and the other an additional sheet of material, which may be an edge of an additional printing master or of a covering sheet. Means may be provided for actuating the clamping jaws independently from each other, means being provided for temporarily securing at least one of the clamping jaws in its position in which the respective clamping device is open. The actuating means for the clamping jaws may each comprise a lever arrangement.

2

Advantageously, one of the clamping jaws is spring loaded, the second clamping jaw being movably arranged on the first clamping jaw. For effecting the opening and closing movements of the second clamping jaw from outside the rotary printing drum, a lever arrangement may be provided outside the printing drum for controlling the opening and closing movements of the second clamping jaw, the lever arrangement comprising a manually operable actuating lever which is arranged for operating, by means of an angular lever, a control member pivoted to the printing drum, the control member being arranged for actuating a release lever on a holder for the first clamping jaw.

In a predetermined, initial, position illustrated in the drawings of a rotatable printing drum 1 of a rotary duplicating machine, a manually operable actuating lever 2 is movable so as to bear against an abutment 22 or against an abutment pin 3. When the said lever 2 is moved to bear against the abutment pin 3 as illustrated in Fig. 1, it is secured in this position by a tension spring 4 which acts as a dead centre spring, while an angular lever 5 rotatable around a shaft 6 bears with a portion 7 acting as a cam against the roller 8a which is mounted on a control member 8 rotatable around a shaft 9 and mounted on the printing drum 1. A fork 11 of the control member 8 rotates a release lever 10 in the direction of the arrow E. The release lever 10 is keyed to a shaft 12 to which also a clamp-opening member 13 is keyed. On a first clamping jaw 14, which serves for attaching a printing master 15 to the printing drum 1, a second clamping jaw 17 is mounted so as to be rotatable around a shaft 16, the second clamping jaw 17 being normally held by a spring 18 in its closed position shown in Fig. 3 in which it bears against the first clamping jaw 14. When the release lever 10 and therewith the clamp-opening member 13 are rotated in the direction of the arrow E, the second clamping jaw 17 is rotated around the shaft 16 since the lever arm 13 engages the cam follower roller 17a mounted on the second clamping jaw 17 whereby a slot 19 is formed between the first clamping jaw 14 and the second clamping jaw 17 so that an edge of an additional printing master or of a covering sheet 20 may freely be inserted into the slot 19.

Fig. 3 shows the first clamping jaw 14 after it has been opened by means of a member 21 actuatable in a manner known per se, so that the first clamping jaw 14 can be operated independently of the operating elements for the second clamping jaw 17 and can be brought into the position

shown in Fig. 3 in which it is ready to receive an edge of the printing master 15.

For moving the clamping jaw 17 from its open position shown in Fig. 1 into its closed position, the manually operable actuating lever 2 is rotated until it bears against the abutment pin 22.

It should be clearly understood that the embodiment described and illustrated is given by way of example. Many modifications, additions and omissions are possible without departing from the spirit and scope of the present invention.

We claim:

1. In a rotary duplicating machine, in combination, a rotary printing drum; a first clamping member movably mounted on said printing drum for clamping a printing master and having a clamping portion; a second clamping member having a clamping portion and being attached to said first clamping member movable relative thereto between a releasing position and a clamping position in which said clamping portions engage each other for clamping an additional sheet; spring means urging said second clamping member into said clamping position; actuating means connected to said second clamping member for moving the same to said releasing position, said actuating means being mounted on said printing drum and having an actuating portion moving along a circular path during rotation of said printing drum; a stationary support; and operating means mounted on said stationary support for movement between an inoperative position and an operative position, and having a portion moving across said path of said actuating portion and engaging the same in a predetermined position of said rotary drum so that movement of said operating means to said operative position effects movement of said actuating means, and thereby movement of said second clamping member to said releasing position, when said rotary drum is in said predetermined angular position with respect to said operating means, while said spring means move said second clamping member to said clamping position when said rotary drum turns out of said predetermined angular position.

2. In a rotary duplicating machine, in combination, a rotary printing drum; a first clamping member movably mounted on said printing drum for clamping a printing master and having a clamping portion; a second clamping member having a clamping portion and being attached to said first clamping member movable relative thereto between a releasing position and a clamping position in which said clamping portions engage each other for clamping an additional sheet; spring means urging said second clamping member into said clamping position; actuating means connected to said second clamping member for moving the same to said releasing position, said actuating means being mounted on said printing drum and having an actuating portion moving along a circular path during rotation of said printing drum; a stationary support; manually operated operating means mounted on said stationary support for movement between an inoperative position and an operative position, and having a portion moving across said path of said actuating portion and engaging the same in a predetermined position of said rotary drum so that movement of said operating means to said operative position effects movement of said actuating means, and thereby movement of said second clamping member to

said releasing position, when said rotary drum is in said predetermined angular position with respect to said operating means, while said spring means move said second clamping member to said clamping position when said rotary drum turns out of said predetermined angular position; and means for arresting said manually operating means in said inoperative and operative positions thereof.

3. In a rotary duplicating machine, in combination, a rotary printing drum; a first clamping member movably mounted within said printing drum for clamping a printing master and having a clamping portion; a shaft means extending parallel to the axis of said rotary printing drum and being mounted on said first clamping member; a second clamping member having a clamping portion and being mounted on said shaft means on said first clamping member rockable between a releasing position and a clamping position in which said clamping portions engage each other for clamping an additional sheet; spring means urging said second clamping member into said clamping position; actuating means connected to said second clamping member for moving the same to said releasing position, said actuating means including an actuating shaft mounted on said printing drum, a lever arm secured to said actuating shaft and having an end portion engaging said second clamping member for turning the same to said releasing position when said actuating shaft is turned, a lever means connected to said actuating shaft for turning the same, said lever means having an actuating portion moving along a circular path during rotation of said printing drum; a stationary support; and operating means mounted on said stationary support for movement between an inoperative position and an operative position, and having a cam portion moving across said path of said actuating portion and engaging the same in a predetermined position of said rotary drum so that movement of said operating means to said operative position effects movement of said actuating means and turning of said actuating shaft, and thereby movement of said second clamping member to said releasing position, when said rotary drum is in said predetermined angular position with respect to said operating means, while said spring means move said second clamping member to said clamping position when said rotary drum turns out of said predetermined angular position.

4. In a rotary duplicating machine, in combination, a rotary printing drum; a first clamping member movably mounted within said printing drum for clamping a printing master and having a clamping portion; a shaft means extending parallel to the axis of said rotary printing drum and being mounted on said first clamping member; a second clamping member having a clamping portion and being mounted on said shaft means on said first clamping member rockable between a releasing position and a clamping position in which said clamping portions engage each other for clamping an additional sheet; spring means urging said second clamping member into said clamping position; actuating means connected to said second clamping member for moving the same to said releasing position, said actuating means including an actuating shaft mounted on said printing drum, a lever arm secured to said actuating shaft and having an end portion engaging said second clamping member for turning the same to said releasing position

when said actuating shaft is turned, a lever means connected to said actuating shaft for turning the same, said lever means having an actuating portion moving along a circular path during rotation of said printing drum; a stationary support; manually operated operating means mounted on said stationary support for movement between an inoperative position and an operative position, and having a cam portion moving across said path of said actuating portion and engaging the same in a predetermined position of said rotary drum so that movement of said operating means to said operative position effects movement of said actuating means and turning of said actuating shaft, and thereby movement of said second clamping member to said releasing position, when said rotary drum is in said predetermined angular position with respect to said operating means, while said spring means move said second clamping member to said clamping position when said rotary drum turns out of said predetermined angular position; and means for arresting said manually operating means in said inoperative and operative positions thereof.

5. An arrangement as claimed in claim 4 wherein in said lever means include another lever arm secured to said actuating shaft, a control member pivotally mounted on said printing drum and having a forked portion engaging the free end of said other lever arm, and a cam follower mounted on said control member and constituting said actuating portion; and wherein said cam portion of said manually operated operating means cooperates with said cam follower.

6. An arrangement as claimed in claim 5 wherein in said manually operated operating means include a first lever pivotally mounted on said stationary support and having a forked end portion; a second double armed lever turnably mounted on said stationary support and having at one end thereof said cam portion; a pin secured to the other end of said second double armed lever and projecting into said forked end portion of said first lever; and comprising stop means engaging said first lever in said operative and inoperative positions of said operating means; and a dead-center spring secured at one end thereof to said stationary support and at the other end thereof to said first lever for urging the same into engagement with said stop means when said first lever is moved out of a dead-center position in which said dead-center spring is located in a plane passing through the turning axis of said first lever.

7. In a rotary duplicating machine, an arrangement as claimed in claim 1 wherein said rotary printing drum is formed with a recess, and wherein in said first clamping member is arranged in said recess of said printing drum.
